UNITED STATES PATENT OFFICE.

COURTLAND F. CARRIER, JR., OF ELMIRA, NEW YORK.

CIRCULATING-PUMP FOR ELECTROLYTIC CELLS.

No. 908,546.

Specification of Letters Patent.

Patented Jan. 5, 1909.

Application filed December 19, 1907. Serial No. 407,202.

To all whom it may concern:

Be it known that I, COURTLAND F. CARRIER, Jr., a citizen of the United States, residing at Elmira, in the county of Chemung and State of New York, have invented certain new and useful Improvements in Circulating-Pumps for Electrolytic Cells, of which the following is a specification.

The object of this invention is to provide 10 in conjunction with the decomposing and oxidizing compartments of an electrolytic cell having a cathode of mercury, an improved means for circulating the mercury between said compartments.

In its preferred form the apparatus 15 comprises a mercury conduit extending between the decomposing and oxidizing compartments of an electrolytic cell, an open, cylindrical pump-well extending upwardly from 20 the conduit, a casing in the pump-well, and a rotary member or rotor in the casing, the rotor, casing and conduits consisting of a non-metallic material and preferably of vitrified earthenware.

The improved circulating pump is of simple construction and easily operated, durable and efficient, and is readily accessible for inspection, cleaning or repair.

In the manufacture of caustic soda by the 25 aid of a mercury cathode, the circulation of the mercury is a very essential factor of the process. In general it is undesirable to raise the mercury through any considerable height, but it is essential in all cases that the 30 flow of the mercury be uniform and quiet, as otherwise the efficiency of the process will be greatly reduced. To produce the desired result all reciprocating parts should be avoided, and this is best attained by the use of a centrifugal pump.

Centrifugal pumps have been heretofore proposed for this use but have proven unsatisfactory in practice, the difficulties lying both in the materials of construction and in 45 the arrangement of parts. I have found that a sufficiently quiet and uniform flow of the mercury may be obtained by a proper form and arrangement of parts whereby the mercury may be impelled by a comparatively slow movement of the rotor, the mercury conduits being of comparatively large cross section and the rotor and casing being designed to present the minimum obstruction to the flow. I have further found that 50 for the best results in the operation of a cell of the character described the use of iron in

the construction of the rotor, casing, conduits or other parts in contact with the mercury must be avoided.

While iron is not affected in the dry state 60 by mercury under ordinary conditions, this is not the case under the conditions of operation of a commercial mercury cell. Sufficient moisture is always carried with the mercury to rust any iron parts with which it 65 comes in contact, and furthermore some iron is always absorbed by the mercury. This iron is found to render the mercury sluggish, to interfere with the electrolytic action of the cell, and to contaminate the product. I 70 provide therefore a construction wherein any contact of the mercury with iron parts is avoided.

A mercury-circulating pump constructed in accordance with my invention is shown in 75 the accompanying drawings, wherein—

Figure 1 is a transverse vertical section through the pump casing and mercury conduits of an electrolytic cell for the production of caustic soda; Fig. 2 is a horizontal 80 section on a larger scale, through the pump and casing on line 2—2 of Fig. 3; Fig. 3 is a central vertical section on line 3—3 of Fig. 2, and Fig. 4 is a perspective view of the rotor, viewed from below.

The general arrangement of parts may be 85 as indicated in Fig. 1, illustrating a cell of the type described in my copending application, Ser. #370,280, filed April 25, 1907, numeral 1 representing the central or decomposing compartment, and 2—2 the lateral or oxidizing compartments.

3 represents the mercury pump, receiving mercury from the oxidizing compartments 2 through conduits 4 and a bottom inlet 5, and 90 discharging the same into a conduit 6 leading to the decomposing compartment.

The circulating apparatus consists essentially of a casing 7, and a rotor 8, the casing being set in a matrix 9 of the best quality of 100 concrete. The rotor and casing are preferably constructed of vitrified earthenware, and the mercury conduits 4 may also consist of vitrified earthenware pipes set in the concrete matrix 9. In the form shown the rotor 105 8 consists of a cylindrical block of vitrified earthenware, having in one end a cylindrical hole 10 for the reception of the shaft 11, the shaft being secured by a cement filling 12 or otherwise. The opposite or lower end of the 110 rotor is provided with a number of vanes 13, shown as four in number, which project from

the end of the cylinder and are formed as an integral part of the same. These vanes are of massive construction to guard against fracture, and are further strengthened by 5 the cylindrical lug 14, which reinforces them for a portion of their length.

The casing consists of a rectangular block 7 of vitrified earthenware, having a recess 15 of a size adapted to receive the rotor; this 10 casing has a bottom inlet 5 for mercury, and a tangential discharge 6 of sufficient size to permit the mercury to escape under minimum pressure. The position of the casing and of the rotor with reference to the mercury 15 in the cells is such that the vanes of the pump are below the level of the mercury when the same is at rest.

Access to the pump is provided by a vertical open pump-well 16, formed in the concrete matrix 9 and of slightly greater diameter than the rotor, thus permitting the rotor to be lifted out and exposing the entire interior of the pump. The mounting of the rotor should preferably be such as to permit 25 its ready removal: it may be entirely supported from above, or it may be carried by a bearing which is supported from the concrete matrix 9. Thus I have shown in the drawing a bearing 17, affording the central 30 bearing surface for a collar 18 on the shaft 11, the bearing 17 being peripherally supported on a ring 19 set in the walls of the well 16, the ring 19 being of sufficient internal diameter to permit the passage of the rotor 8. The 35 shaft may be rotated by any suitable means, as bevel gears.

It will be noted that the construction and dimensions of the conduits, pump casing and rotor are such as to provide a minimum of 40 obstruction to the flow of the mercury.

With this construction it is found that a rotation not exceeding 100—200 revolutions per minute will cause a quiet and uniform movement of the mercury through the outlet 6. The simplicity of the apparatus reduces the wear to a minimum, and the absence of all metal from parts in contact with the mercury entirely avoids contamination 45 of the product.

50 I claim:

1. In combination with the decomposing and oxidizing compartments of an electrolytic cell having a mercury cathode, a mer-

cury conduit extending between said compartments, a pump casing in said conduit, 55 and a rotor in said casing, said conduits, casing and rotor consisting of non-metallic material.

2. In combination with the decomposing and oxidizing compartments of an electrolytic cell having a mercury cathode, a mercury conduit extending between said compartments, a pump casing in said conduit, 60 and a rotor in said casing, said casing and rotor consisting of vitrified earthenware. 65

3. In combination with the decomposing and oxidizing compartments of an electrolytic cell having a mercury cathode, a mercury conduit extending between said compartments, a pump-well opening upwardly 70 from said conduit, and a rotor in said well, said rotor of less diameter than said well, the parts in contact with the mercury consisting of non-metallic material.

4. In combination with the decomposing and oxidizing compartments of an electrolytic cell having a mercury cathode, a mercury conduit extending between said compartments, a pump casing in said conduit, 75 and a non-metallic rotor in said casing, said 80 rotor comprising a cylinder having vanes projecting from its lower surface.

5. In combination with the decomposing and oxidizing compartments of an electrolytic cell having a mercury cathode, a mercury conduit extending between said compartments, a pump casing in said conduit, 85 and a rotor in said casing, said rotor comprising a cylinder having substantially radial vanes projecting from its lower surface and 90 terminating at the periphery of the cylinder.

6. In combination with the decomposing and oxidizing compartments of an electrolytic cell having a mercury cathode, a mercury conduit extending between said compartments, a pump casing in said conduit having an axial bottom inlet for mercury, 95 and a rotor in said casing, said casing and rotor consisting of non-metallic material.

In testimony whereof, I affix my signature 100 in presence of two witnesses.

COURTLAND F. CARRIER, JR.
